(57) **CLAIM**

The ornamental design for a sensor bracket, as shown and described.

DESCRIPTION

FIG. 1 is a front, top, and right side perspective view of a sensor bracket showing our new design;

FIG. 2 is a rear, top, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof, a bottom view being a mirror image thereof; and,

FIG. 8 is front, top, and right side perspective view of the sensor bracket in a separated condition.

The dashed broken lines in the figures show portions of the sensor bracket that form no part of the claimed design. The dot-dashed broken lines in the figures represent boundaries that form no part of the claimed design.
